[57] **CLAIM**

We claim the ornamental design for a frame member for a cart, as shown and described.

DESCRIPTION

FIG. 1 is a top and front perspective view of a frame member for cart showing our new design;

FIG. 2 is a front elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a top and front perspective view of a second embodiment of the frame member for a cart;

FIG. 8 is a front elevational view of FIG. 7;

FIG. 9 is a top plan view of FIG. 7;

FIG. 10 is a bottom plan view of FIG. 7;

FIG. 11 is a left side elevational view of FIG. 7; and,

FIG. 12 is a right side elevational view of FIG. 7.

The broken lines showing a cart and portions of a frame member for the cart in FIGS. 1-12 are for illustrative purposes only and form no part of the claimed design.
